United States Patent Office.

JOHN J. COWELL, OF NEWARK, NEW JERSEY.

Letters Patent No. 90,504, dated May 25, 1869.

IMPROVED HINGE AND SPRING COMBINED.

The Schedule referred to in these Letters Patent and making part of the same.

To all whom it may concern:

Be it known that I, JOHN J. COWELL, of Newark, in the county of Essex, and in the State of New Jersey, have invented new and useful Improvements in Hinges; and do hereby declare that the following is a full, clear, and exact description thereof, reference being had to the accompanying drawings, and to the letters of reference marked thereon.

The nature of my invention consists in the construction of a hinge, which shall at the same time act as, and in fact be a spring for closing gates, and which, by a very slight modification, may be used as a door-spring.

In order to enable others skilled in the art to which my invention appertains, to make and use the same, I will now proceed to describe its construction and operation, referring to the annexed drawings, which form a part of this specification, and in which—

Figure 1 is a perspective of the casing, showing the spring inside of the same;

Figure 2 is a perspective of the arm, forming, with the casing, the hinge; and

Figure 3 is a plan view of a door, showing my invention adapted as a door-spring.

Figure 4 is a cross-section of the top of the casing.

A represents a metal casing of suitable size, open at the inner side, and provided with ears or flanges B, having holes for the insertion of screws, that the same may be attached to a gate-post.

Through the casing A runs a vertical shaft, C, having its bearings in the top and bottom of the casing, and around which is placed a spiral or coil-spring, D, the lower end of which spring is inserted in a hole in the bottom of the casing, and the upper end inserted in a hole in the shaft C, thus connecting the shaft to the casing.

The spring D may be tightened or loosened by changing the position of its lower end.

The shaft C is prevented from turning more than a certain distance by a pin, a, inserted in said shaft, near the top of the casing, which pin bears against a flange or projection on the inner side of the casing.

The upper end of the shaft C passes through the top of the casing A, and is cut square above the same, as seen in fig. 1.

E represents an arm, of suitable size and shape to be attached to the gate, and the outer end of which arm is provided with a square hole to fit on the end of the shaft C, thus forming an ordinary lift-off hinge, with the addition of the spring, which acts so as to close the gate whenever the same has been opened.

This hinge may be used as a common door-spring by securing the casing to the upper part of the door, and substituting an arm, F, having a hook at its outer end, in place of the arm E, the hook on the arm F to be connected by a rod or link, G, to the upper sill of the door, as shown in fig. 4.

Having thus fully described my invention,

What I claim as new, and desire to secure by Letters Patent, is—

The arrangement, with the casing A, shaft C, and spring D, of the arms E and F, and rod or link G, so as to form a combined hinge and spring, or spring alone, substantially as herein set forth.

In testimony that I claim the foregoing, I have hereunto set my hand, this 25th day of February, 1869.

JNO. J. COWELL.
